UNITED STATES PATENT OFFICE.

JOHN RANK, OF MINNEAPOLIS, MINNESOTA.

GREASE-CUP.

1,074,291.

Specification of Letters Patent. Patented Sept. 30, 1913.

Application filed November 2, 1911. Serial No. 658,111.

To all whom it may concern:

Be it known that I, JOHN RANK, a citizen of the United States, residing at Minneapolis, in the county of Hennepin and State of Minnesota, have invented certain new and useful Improvements in Grease-Cups; and I do hereby declare the following to be a full, clear, and exact description of the invention, such as will enable others skilled 10 in the art to which it appertains to make and use the same.

My present invention relates to grease cups for journals and bearings generally, but is particularly designed as an improvement 15 on that type of grease cups which is disclosed and broadly claimed in my prior Patent No. 901,089, of date, October 13th, 1908.

Generally stated, the invention consists 20 of the novel devices and combinations of devices hereinafter described and defined in the claims.

In the said prior patent, the grease cup was provided with a detachable cover, a 25 feed rod extended through the cover and the discharge nipple of the cup, stop collars on said feed rod above and below the cover, and a feed head adjustable on said feed rod for coöperation with the discharge nipple of 30 said cup. In this prior arrangement, it was necessary to remove the cover in order to adjust the feed head on the rod, to thereby vary the feeding action. In the present improved form of the grease cup, the feed 35 head is provided with a long sleeve that is extended through the cover, and the stop collars above and below the cover are directly secured on the said sleeve, and the said sleeve is provided with means for ad- 40 justably securing it on the said rod, so that thereby, the said feed head may be adjusted on said rod without removing the said cover.

The present invention also includes an improved form of nipple detachably secured 45 to the bottom of the cup, and whereby the manufacture of the cup is simplified and reduced to a minimum of cost. These nipples are provided with threaded shanks all of the same diameter and thread, at that end 50 which connects with the cup, but the other ends of the said nipples are made in different sizes so as to fit different threaded sockets or seats in different bearings or journals.

In the accompanying drawings which 55 illustrate the invention, like characters in-

dicate like parts throughout the several views.

Referring to the drawings, Figure 1 is a view chiefly in side elevation, but with some parts sectioned, and some parts broken away, showing the improved grease cup applied to a crank rod and wrist pin journal; Fig. 2 is a side elevation of a cup showing the same removed from the journal; Fig. 3 is a side elevation of the body of the cup, 65 other parts being removed; Fig. 4 is a fragmentary section on the line $x^4 x^4$ of Fig. 3; Fig. 5 shows the feed rod and the feed head with its long sleeve, the latter being sectioned; and Fig. 6 is a detail in section 70 showing one of the interchangeably usable nipples of the feed cup.

The numeral 1 indicates a crank shaft having a crank 2 with an ordinary wrist pin 3. The numeral 4 indicates a crank rod 75 having a bearing 5 working on the wrist pin 3. All of these parts are, or may be, of standard or any suitable construction.

The body of the feed cup, or in other words, the feed cup proper, is indicated by 80 the numeral 6 and is preferably of the form shown in the drawings. At its contracted lower end, the said feed cup 6 has an internally threaded seat that is adapted to receive one end of a nipple 7, which is threaded at 85 both ends, and preferably formed with an intermediate angular portion 8 to which a wrench may be applied. The lower or ex- 90 tended end of the nipple is threaded at 7^a to adapt it to be screwed into a correspondingly threaded seat in the bearing, to-wit, as shown into a strap 5^a of the crank rod 4. The said nipples will be made with threaded ends 7^a of different diameter, so that they will fit threaded seats of different sizes. 95 This adapts the grease cup to be easily and quickly applied to bearings or journals having threaded seats of different diameters or threads of different pitch simply by selec- 100 tion of a proper nipple, and without making it necessary to carry as large a stock of grease cups as would otherwise be necessary.

The cover 9 of the grease cup is prefer- 105 ably detachably secured to the cup by an ordinary bayonet joint 10, although it may be otherwise secured.

The feed rod 11 is preferably made from copper, and is passed through an axial per- 110 foration in the cover 9, through the nipple 7, and through a suitable passage 12 in the

bearing 5. This passage 12 is of considerably larger diameter than the said feed rod, so as to permit a proper feeding of the oil to the journal. The lower end of the said rod 5 bears lightly against the wrist pin 3.

Within the feed cup, for coöperation with the passage in the nipple 7, is a feed head 13 preferably of conical form. This feed head 13, in accordance with my invention, and as 10 already stated, is provided with a long sleeve 14 that is extended through the axial passage in the cover 9. At its upper and outer end, the sleeve 14 is provided with a set screw 15 for rigidly but adjustably securing 15 said sleeve and feed head on the said rod. Stop collars 16 and 17 are adjustably secured on the sleeve 14, respectively, below and above the cover 9, preferably by means of set screws 18.

20 The amount of grease or oil that will be fed to the journal will depend first, on the amount of endwise movement which is permitted to the rod 11 and feed head 13 which is carried thereby, and second, it will also 25 depend on the distance that the said feed head is normally set away from the coöperating end of the nipple. The amount of endwise movement which will be given to the feed rod and feed head is determined by 30 the adjustments of the collars 16 and 17 in respect to the cover 9. In most instances, the said collars will be so set that more or less endwise movement of the feed rod will be permitted, but for very high speeds, it 35 frequently is desirable to secure the feed rod and feed head against endwise movements. And this, as is evident, may be accomplished by setting the stop collars 16 and 17 in engagement with the said cover 9. When this 40 is done, the amount of oil that will be fed will depend on the adjustment of the feed head 13 in respect to the nipple. Usually the wrist pin or rotating member of the journal will be provided with a peripheral oil-way or groove which will pass the lower end 45 of the rod 11, and hence, the outer stop collar 17 is usually so adjusted that the lower end of the said rod 11 will lightly engage the rotating member of the journal but cannot 50 drop into the oil-way thereof.

With this improved arrangement, as already stated, the sleeve 14, and hence the feed head 13 thereof, may be adjusted on the rod 11 without removing the cover 9 and 55 without getting the fingers into contact with the grease which is contained within the cup. Even when the inner collar 16 is to be adjusted, it is only necessary to raise the cover and rod and the said inner collar can 60 then be adjusted without digging deep into the grease, and without entirely removing the rod or the sleeve from the grease.

The interchangeable nipples above described, are capable of use on grease cups generally, regardless of whether or not they 65 are provided with the improved feed rod and sleeve.

What I claim is:

1. The combination with a feed cup having a cover and a discharge passage, of a 70 feed rod extended through said discharge passage, a sleeve adjustably mounted on said rod extended through said cover, and means for adjustably securing said sleeve in respect to said cover, operative from the exterior of said cover.

2. The combination with a feed cup having a cover and a discharge passage, of a feed rod extended through said discharge passage, a feed head on said rod, having a 80 sleeve extended through said cover, and means for adjusting said feed head and sleeve from the exterior of said cup.

3. The combination with a feed cup having a cover and a discharge passage, of a 85 feed rod extended through said discharge passage and through said cover, a sleeve on said rod extended through said cover, means for adjustably securing said sleeve on said feed rod from the exterior of said cup, and 90 means for adjusting said sleeve in respect to said cover.

4. The combination with a feed cup having a cover and a discharge nipple, of a feed rod extended through said discharge nipple 95 and cover, a feed head on said rod coöperating with said discharge nipple and provided with a long sleeve extending through said cover, means applied to the outer end of said sleeve, for adjustably securing the same on 100 said feed rod, and stop collars, one above and one below said cover, adjustably secured on said sleeve.

5. The combination with a feed cup having a detachable cover and a discharge nipple, of a feed rod extended through said discharge nipple and through said cover, a feed head on said rod coöperating with said discharge nipple and provided with a long sleeve also extended through said cover, stop 110 collars on said sleeve one above and one below said cover, and set screws applied to said collars and to said sleeve for adjustably securing said collars on said sleeve and said sleeve on said rod, the said screw for securing said sleeve being located above said cover and the upper collar, substantially as described.

In testimony whereof I affix my signature in presence of two witnesses.

JOHN RANK.
